UNITED STATES PATENT OFFICE.

GORHAM CROSBY, OF GLEN RIDGE, NEW JERSEY, ASSIGNOR TO GOULD COUPLER COMPANY, A CORPORATION OF NEW YORK.

REGULATION OF ELECTRICAL SYSTEMS.

1,290,917.

Specification of Letters Patent.

Patented Jan. 14, 1919.

Application filed June 24, 1915. Serial No. 36,031.

To all whom it may concern:

Be it known that I, GORHAM CROSBY, a citizen of the United States, and a resident of Glen Ridge, county of Essex, State of New Jersey, have invented certain new and useful Improvements in the Regulation of Electrical Systems, of which the following is a specification.

My invention relates to the regulation of electrical systems, more particularly by the inclusion in the circuit to be regulated of two variable resistances controlled in a manner to produce more efficient regulation.

In many systems in which the work circuit is supplied from a source of variable voltage, such as in car lighting systems, wherein a generator and storage battery are employed in operative relation to a work circuit or work circuits, it has been common to employ a compressible variable resistance in series between the battery and work circuit in regulating the voltage applied to the latter. If the load on the work circuit or circuits is very heavy, it is found that either the compressible variable resistance or carbon pile must be so large as to be unwieldy and impractical or else the load will exhaust the capacity of the variable resistance. According to my invention I overcome these difficulties by including in series with the carbon pile variable resistance, a second variable resistance which may be of carbon pile type and which I preferably operate to increase the resistance thereof, when the voltage of the source is materially higher than that across the work circuit.

Further objects, features and advantages will more clearly appear from the detailed description given below, taken in connection with the accompanying drawings, which form a part of this specification.

In the drawings, Figure 1 is a diagram of a train lighting system, embodying my invention in one form. Fig. 2 is a similar diagram, illustrating a modification. Fig. 3 is a diagram of part of a similar system, illustrating a further modification. Fig. 4 is a diagram of a similar system illustrating another modification.

Referring to Fig. 1, 1 represents the main generator, which may be driven at variable speed, as from a car axle of a train. The generator 1 supplies the mains 2, 3 and 4. The main 4 branches off from the main 3. 5 represents a shunt field of the generator 1,

having in series therewith a carbon pile variable resistance 6, the pressure upon one end of which is varied by a lever 7, operated by a solenoid 9, whose windings are connected across the terminals of the generator, 60 to be responsive to voltage variations thereof. The pressure upon the other end of the pile is controlled by a lever 10, operated by a solenoid 11, connected in series with the generator, so as to be responsive to current 65 variations in its total output. 12, 12, represent storage batteries, which may be located in separate cars of the train, connected across the mains or train line conductors 2 and 3. 13, 13, represent work circuits, 70 which may also be placed in separate cars of the train and connected across the mains or train line conductors 2 and 4.

When the generator is running at sufficient speed to supply the work circuits, its 75 voltage is regulated to maintain a constant output by means of solenoid 11 acting upon the pile 6, varying the strength of the coil 5 in a well known manner. When the batteries have become substantially charged, 80 which is indicated by a rise in voltage, with a consequent rise in generator voltage, the coil 9 becomes sufficiently energized to relieve the pressure on the other end of the pile 6 through the lever 7, so that thereafter 85 the generator voltage is maintained substantially constant, causing a decrease in the generator output and the stopping of the charging of the batteries. This weakens the solenoid 11 so that when solenoid 9 comes 90 into action, it assumes control of the generator.

Connected in the main 4, between the various batteries and various work circuits are two carbon pile variable resistances 14 95 and 15. The pressure upon the pile 14 is controlled by a lever 16, operated by a solenoid 17, connected in circuit across the mains 2 and 4 of the work circuit and having in series therewith carbon pile 18, operated by a lever 19, controlled by a solenoid 20, connected in shunt across the work circuits. 21 represents a small carbon pile, the pressure upon which is varied by lever 22, by engagement therewith of a projection 23 carried upon lever 16, so that when the coil 17 is weakened to a certain extent, allowing its core to drop, the member 23 on lever 16 engages the lever 22 and causes it to compress the pile 21. The pile 21 is then 110

connected in shunt across the pile 14, the circuit being through conductor 24, member 23, lever 22, pile 21 and conductor 25. Thus, when the pile 14 is compressed substantially to its maximum, the pile 21 is thrown in shunt therewith by engagement of member 23 with lever 22, and upon further depression of the pile 21, the resistance that is regularly maintained between 5 the batteries and the lamps is practically *nil*. The carbon pile 15 is similarly operated upon by a lever 26, controlled by a solenoid 27, connected across the work circuit and having in series therewith carbon 10 pile 28, the pressure upon which is controlled by lever 29, which is operated by the solenoid 20 when a pin 30, carried on a spindle 31, connected to the lower end of the core of the solenoid 20, engages the lever 15 29 to raise the same. A small carbon pile 32 operated upon by a lever 33, engaged by projection 34 on lever 26, is arranged in shunt with pile 15, and operated in a manner similar to that described with respect 20 to pile 21. The pile 15 is normally maintained under substantially maximum compression with pile 32 compressed by the lever 33.

When the voltage across the variable 30 source tends to increase, thus increasing the strength of solenoid 20, it, through lever 19, compresses pile 18, thereby increasing the strength of solenoid 17, relieving the pressure on pile 14, so as to increase the resistance in series with the work circuit and maintain the voltage across the work circuit or work circuits substantially constant. The tendency for the voltage across the work circuits to decrease results in the weakening 35 of solenoid 20, increasing resistance in pile 18, weakening of solenoid 17 and decrease of resistance of pile 14, to maintain the voltage across the work circuits substantially constant. As the batteries become charged, 40 as above explained, and when the voltage across the generator and batteries is materially higher than that across the work circuits, the solenoid 20 will have raised its core sufficiently for the pin 30 to engage the lever 29, thereby decreasing the resistance of pile 28, increasing the strength of the solenoid 27, causing the lever 26 to relieve the pressure on pile 15, so that the resistance 45 of the pile 15 will be increased. This results in the pile 15 taking a material portion of the voltage drop between the generator and batteries on one side and the work circuits on the other, so that pile 14 is not required to take the heavy current 50 with a large voltage drop and in a greatly expanded condition, which would likely be beyond its capacity. Part of the drop being carried by pile 15, the pile 14 is able to take care of the heavy current by reason of 55 the fact that the drop thereacross is not

large and it may be in a more or less compressed condition. In order that the pile 14 need not be further affected by variations in pile 18 after pile 15 has begun to be affected by the variations caused in pile 28, 70 I have shown pile 18 provided with a yielding abutment comprising the pivoted lever 45 which is drawn toward the pile by the tension of the spring 46. When the lever 19 has been moved far enough to compress 75 pile 18 sufficiently to overcome the pressure of the spring 46 further movement of the lever has no substantial effect in decreasing the resistance of pile 18 and therefore no substantial indirect effect in increasing the resistance of carbon pile 14. After this point is reached further regulation can be effected practically alone by the compression of pile 28 and its effect in increasing the resistance of pile 15. It will thus be seen 80 that the pile 14 operates throughout a certain range in voltage variations of the source while the pile 15 operates throughout a different range of voltage variations.

In the modification shown in Fig. 2, similar reference characters refer to similar parts, and the system illustrated is substantially the same except that the coil 11 is shown connected in series with the batteries and not in series with the work circuits, 95 so that it acts to regulate the generator for constant battery current. Also the pilot regulators 18 and 28 have been omitted, the pile 14 being shown as controlled for voltage changes across the work circuit directly by 100 the solenoid 17, while the pile 15 is controlled by a solenoid having a voltage winding 40 connected across compressible resistance 14, so as to be responsive to voltage changes thereacross and a current winding 105 41 connected in series with the various work circuits. It will thus be seen that the solenoid comprising windings 40 and 41 act responsive to changes in load (both voltage and current) carried by the carbon pile 14, 110 and the solenoid is attracted to increase the circuit resistance at 15, only when the carbon pile 14 becomes overloaded. That is, the coils 40 and 41 are wound to aid one another, but do not have sufficient strength to 115 raise their core and relieve pressure on the pile 15 until the pile 14 has become overloaded.

The arrangement illustrated in Fig. 3 is the same as that of Fig. 2, except that coil 120 41 is omitted, so that resistance in pile 15 is increased only when the voltage across the pile 14 increases to a predetermined point, indicating that the pile 14 would be overloaded by a further increase in voltage.

In Fig. 4 there is shown a similar arrangement, except that coil 40 is shown connected across the generator and batteries and is designed to operate the lever 26 to relieve pressure on the pile 15 in a similar 130

manner when the voltage across the generator and batteries is materially higher than that across the work circuits.

- Thus, in each of the arrangements shown
- 5 a second variable resistance is provided in series with a compressible variable resistance, and the second variable resistance is controlled to increase the resistance in series with the first, when there is danger of the
  - 10 first becoming overloaded, as indicated by a material increase in voltage of the source over that of the work circuit. It will be understood that if desired, suitable pilot or magnifying regulators, such as shown at 18,
  - 15 20, in Fig. 1, may be provided for the solenoids 17 and 40 in the other figures.

Although I have described my improvements in great detail and with respect to car lighting systems, I do not desire to be limited to such details, as obviously, my improvements may be applied to many other systems and to many situations, and I intend to cover all arrangements coming within the language of the appended claims.

- 25 Having fully and clearly described my improvements, what I claim as new and desire to secure by Letters Patent is:—

1. In an electrical system of distribution, the combination of a source of variable voltage, a work circuit supplied thereby, a carbon pile in series with the work circuit for regulating the voltage applied thereto, a variable resistance in series with said pile, and means for increasing the resistance of
- 35 said variable resistance when the voltage of the source is relatively high, said means comprising a controlling coil responsive to variations in voltage across said carbon pile.

2. In an electrical system of distribution,
- 40 a circuit to be regulated, a compressible variable resistance regulating said circuit, a second variable resistance in series with the compressible variable resistance, and means for increasing the resistance of said second
- 45 variable resistance responsive to variations in voltage across said compressible variable resistance.

3. In an electrical system of distribution having a work circuit supplied from a source
- 50 of variable voltage, a variable resistance in series with the work circuit controlled to maintain substantially constant work circuit

voltage, a second variable resistance in series in said work circuit, and means for controlling it responsively to voltage drop across

55 the first resistance.

4. A circuit supplied from a source of variable voltage and to be regulated for constant voltage having in series therewith two carbon piles one controlled by the voltage
- 60 of said circuit and the other having its controlling means brought into action when the resistance value of the first has been increased to a predetermined amount.

5. A circuit supplied from a source of variable voltage and to be regulated for constant voltage having a carbon pile in series therewith, and means for increasing its resistance to a given value with increases of voltage of said source to maintain
- 65 substantially constant voltage applied to said circuit, a second carbon pile in series with said circuit and means acting when said given value of the first pile has been reached for increasing its resistance with further increases of voltage from said source.

6. A circuit to be regulated from a source of variable voltage, two carbon piles in series therewith, a voltage coil, means whereby said coil controls one of said piles until
- 70 the same increases to a given value and whereby said coil controls the second pile when the voltage of the source further increases without further acting on the first pile.

7. In an electrical system of distribution having a work circuit supplied from a source of variable voltage, a regulating mechanism controlling the work circuit voltage including a carbon pile resistance in series with the
- 75 work circuit and means for varying the resistance responsive to momentary variations of work circuit voltage, a second variable resistance in series with said carbon pile and means for varying said second resistance to
- 80 maintain constant work circuit voltage when the resistance value of the carbon pile has increased to a desired value and for maintaining the said value throughout the variations of said second resistance.

In testimony whereof, I have signed my name to this specification.

GORHAM CROSBY.
